MERLE PEABODY CHAPLIN, OF WHITE PLAINS, NEW YORK, ASSIGNOR TO WESTERN ELECTRIC COMPANY, INCORPORATED, OF NEW YORK, N. Y., A CORPORATION OF NEW YORK.

STEPPING MECHANISM.

Application filed August 5, 1924. Serial No. 730,178.

This invention relates to selector switches, and more particularly to selector switches used in automatic telephone systems. It is especially adapted for use in automatic telephone systems wherein selector switches are set under control of direct current impulses produced by a dial or some other similar impulse sending mechanism.

There are a number of selector switches comprising stepping devices known and used in connection with impulse senders. In using these devices, it has been found that the selector switch will not function properly if the impulses produced by the impulse sender are distorted, and it has been found necessary to provide a circuit arrangement sometimes known as an auxiliary or booster circuit for insuring the proper operation of the selector switch.

In conjunction with the selector switches heretofore used, it has been necessary to employ a sensitive relay, generally known as an impulse relay, which has been made responsive to the impulses produced by the impulse sender or dial, and which in turn has reproduced impulses for setting the selector switch. It has been found necessary to employ an impulse relay in this manner because owing to the selector switch load, which the stepping mechanism is required to drive, it has heretofore been found impractical to operate the stepping mechanism directly under control of the impulse sender even though the impulses supplied to the stepping mechanism are not distorted.

The object of this invention is a selector switch which will operate properly, even though the impulses are somewhat distorted, without the aid of a booster circuit.

Another object of this invention is a selector switch capable of responding directly to the impulses produced by the dial or other impulse sending mechanism.

A feature of this invention is the use of two electromagnets, one of heavy and powerful construction capable of performing a considerable amount of work, and the other of light construction capable of high speed operation and designed to perform only a small amount of work, with an interlocking arrangement controlled by both electromagnets to provide for maintaining the same interrelation of members.

Another feature of this invention is the adjusting arrangement for the pawl of the high speed electromagnet.

Another feature of this invention is the unitary structure and adjusting arrangement of the contact controlling mechanism.

Other features will appear from the detailed description.

In accordance with this invention, an electromagnet of light construction and which is accordingly very sensitive and capable of operating at high speed, is set under control of direct current impulses produced by a subscriber's dial. As soon as this electromagnet is energized, a circuit is closed for a second electromagnet of heavy and powerful construction which drives the load of the selector switch. This second electromagnet is self-interrupting and accordingly steps until it attains the setting previously taken by the sensitive electromagnet, when its energizing circuit is opened and it once more comes to rest, the brushes of the selector switch being then set in accordance with the number of impulses produced originally by the subscriber's dial.

In the drawing comprising but a single sheet, the invention is diagrammatically illustrated.

Fig. 1 represents a front view of the switch while Fig. 2 represents a side view.

Fig. 3 is a detailed view of the interlocking ratchets shown in the structure in Fig. 1.

Fig. 4 shows the circuit connections of the electromagnets for setting the switch.

Fig. 5 shows one circuit arrangement which may be used for returning the switch to its normal position when its cycle of operations is completed.

Fig. 6 shows another circuit arrangement which may be used for returning the switch to its normal position.

The structure consists of a sensitive electromagnet 1, adjustably secured at 2 to the bracket 44, which is permanently secured at 4 to the main frame 5 of the switch. The armature 6 of the sensitive electromagnet 1, is pivoted at 7. To an extension piece 9 of the armature 6 is secured at 10, the pawl 11

for driving the ratchet 22. The spring 8 serves to restore the armature 6, after the circuit for the electromagnet 1 is opened, and the back stop screw 45 serves, among other purposes, to limit the return movement of the armature 6.

The relation between the fulcrum 7 and the pole piece of the electromagnet 1 is fixed, and the adjustment of the pawl 11 with relation to the ratchet 22 is obtained by means of twin clamp screws by means of which the sensitive electromagnet 1 is adjustably secured at 2 to the bracket 44.

The driving electromagnet 12 is screwed at 46 to the bracket 47, which is in turn secured at 14 and 15 to the main frame 5 of the selector switch. The driving armature 16 of the driving electromagnet 12 is a lever whose fulcrum is at 17. The driving armature 16 is extended at 18, and the driving pawl 20 is adjustably secured at 19 to this extension arm of the driving armature. The driving pawl 20 operates the ratchet 21, to which is connected the main lead of the selector switch.

The relation between the fulcrum 17 and the pole piece of the driving electromagnet 12 is fixed and the pawl 20 is adjusted with respect to the ratchet 21 by means of the adjusting screws shown at 19.

It will be observed that the spring 48 for driving the ratchet 21 and the main load, the pole piece of the electromagnet 12, and the load connected to the ratchet 21 are all on the same side of the pivot 17, and are all in the same plane. The spring 43 is provided to maintain the driving armature 16 in the proper position with respect to its fulcrum 17, it also serves to assist the main driving spring 48.

The mechanism for controlling the opening and closing of contact springs 41 and 42 as well as the springs themselves is all assembled as a unit and is adjustably secured to the main frame 5 by means of screws 49 and 50.

Pole piece 38 for the auxiliary armature 37 is brought in close proximity to the magnet 12 at a point 29 by means of the extension member 28 to provide magnetic flux for holding auxiliary armature 37.

It will be observed that the unitary structure of the contact controlling mechanism is pivoted at 51 on the face of the main frame 5 so that the position of the unit with respect to the driving armature 16 of the electromagnet 12 may be varied by means of the screws 49 and 50. The auxiliary armature 37 is secured at 52 to the unitary structure. The position of this armature controls the opening and closing of the contact springs 41 and 42 of the interrupter which is included in the electrical circuit of the electromagnet 12. The back-stop screw 53 which is adjustable, determines,

among other things, the limit of the backward movement of the driving armature 16.

When the driving armature 16 is at rest, the flexible spring 40 presses against the auxiliary armature 37, forcing it into physical contact with the pole piece 38 and by overcoming the opposing tension of the contact spring 41 closing the contacts of the contact springs 41 and 42. When the armature 16 is first attracted by the magnetization of the pole piece of the driving electromagnet 12, the auxiliary armature 37 is held against the pole piece 38, and the contact springs 41 and 42 are maintained closed. When the driving armature 16 approaches the limit of its forward movement however, the lug 39 pressing against the auxiliary armature 37 forces it away from the pole piece 38. The contact springs 41 and 42 are thus opened and interrupt the electrical circuit of the driving electromagnet 12.

The sensitive electromagnet 1 is used to drive the ratchet 22, and the driving electromagnet 12 is used to drive the ratchet 21. The ratchets 21 and 22 are freely and independently mounted upon the shaft 23. As

more clearly indicated in Fig. 3, the ratchet 22 is equipped with a cam 34 and the ratchet 21 is similarly equipped with a cam 35. In the normal position of the switch, the cams 34 and 35 are in the position with respect to each other shown in Fig. 1. Whenever the ratchets 21 and 22 are not in the position with respect to each other which is shown in Fig. 1, the cams 34 and 35 will be in a position shown in Fig. 3, in which case the contact springs 26 and 27 will be allowed to close by the action of the lever 24. When the ratchets 21 and 22 are in the position with respect to each other indicated in Fig. 1, the lever 24 overcomes the tension of the contact spring 26 at the point 25, maintaining contact springs 26 and 27 open, but when the ratchets 21 and 22 are in the position indicated in Fig. 3, the tension exerted at 25 upon the contact spring 26 by the lever 24 is removed, and the contact springs 26 and 27 are closed.

The principle of operation is as follows: The sensitive electromagnet 1 is connected directly or under control of an impulse relay as desired, to an impulse sender. Let us assume the electromagnet 1 is directly connected to the dial 36 (Fig. 4). When the dial 36 is operated and released, the circuit through the electromagnet 1 is interrupted and the electromagnet 1 which is very sensitive, responds to the impulses thus produced, and the ratchet 22 is rotated by means of the pawl 11 controlled by the armature 6. The ratchet 22 advances step by step, depending upon the number of impulses transmitted in accordance with the digit dialed, and finally comes to rest at the end of the impulse train. As soon as the ratchet 22 is advanced

one step, the cams 34 and 35 assume the position shown in Fig. 3 and the contact springs 26 and 27 are closed, thus completing the electrical circuit for the driving electromagnet 12. The electromagnet 12 is now energized causing the driving armature 16 to move forward, thus disengaging the main driving pawl 20 from a tooth of the ratchet 21. The driving armature 16 continues to move forward until the main driving pawl 20 engages a new tooth in the ratchet 21 at which moment the lug 29 engages the auxiliary armature 37, forcing it away from the pole piece 38 thus opening the magnetic circuit including the armature 37 and the pole piece 38. The contact springs 41 and 42 are now opened by virtue of their spring tension, thus opening the electrical circuit for the driving electromagnet 12 which is deenergized. The main driving spring 48 and the fulcrum maintaining spring 43, which were tensioned during the forward movement of the main driving armature 16, now retract, and in so doing initiate the backward movement of main armature 16 and cause the main driving pawl 20 to rotate the ratchet 21 one step. During the return movement of the main driving armature 16, the flexible spring 40 engages with the auxiliary armature 37, forcing it once more into contact with the pole piece 38. In this position, the contact springs 41 and 42 are once more closed and the cycle of operations is repeated. It should be understood that when the flexible spring 40 is disengaged from the armature 37 during the forward movement of the main driving armature 16, the armature 37 remains in physical contact with pole piece 38, due to the magnetic flux in the magnetic circuit including the auxiliary magnet armature 37 and pole piece 38. So long as the armature 37 is in contact with the pole piece 38, the contact springs 41 and 42 remain closed. This cycle of operations of the driving electromagnet 12 is repeated, until the ratchet 21 is once more in the position with relation to ratchet 22 which is shown in Fig. 1, when the contact springs 26 and 27 are opened by the action of the lever 24 under control of the ratchet 22.

The ratchet 22 associated with the sensitive electromagnet 1, is entirely independent of the ratchet 21 associated with the driving electromagnet 12. The sensitive electromagnet 1 is capable of high speed operation and will follow the impulses produced by the dial 36. The electromagnet 12 is of heavy and powerful construction and is designed to perform a considerable amount of work. As applied in this disclosure, its function is to drive the brush load of the selector switch. It is obvious therefore that the electromagnet 12 will be comparatively slower in operation than the sensitive electromagnet 1, but as its speed of operation is

not dependent upon the dial 36, this is not important. The electromagnet 12 therefore may operate and step the ratchet 21 as slowly as is necessary to the proper operation of the stepping mechanism, without in any way depending upon the speed of the dial 36 or the sensitive electromagnet 1 for its time of operation. When the ratchets 21 and 22 are again properly interlocked they will occupy the position with respect to each other indicated in Fig. 1 and the circuit controlled by the contact springs 26 and 27 will be opened preventing the electromagnet 12 from reoperating. The brushes 54 will now be properly centered upon a certain set of terminals in the terminal bank of the selector switch.

The return to normal of the switch may be controlled in various ways. Two typical methods of accomplishing the return to normal are shown in Figs. 5 and 6.

In the arrangement shown in Fig. 5, the return to normal is accomplished in the following manner. An arc of terminals 55 is provided and all the terminals except those representing the normal position of the switch are strapped together as shown. When it is desired to return the switch to normal, the contact 42 is disconnected from the contact 27 and is connected to battery, at the same time the conductor 56 is closed connecting ground to all the terminals of the arc 55. A circuit is now closed from battery by way of contact 42 and armature 41, through the windings of the electromagnets 1 and 12 in parallel, brush 57, any strapped terminal in the arc 55, conductor 56, to ground. The electromagnet 1 being sensitive operates immediately, but the electromagnet 12 which is driving the switch load is slower in operation. When the electromagnet 12 finally operates, the circuit is opened at 42 and the sensitive electromagnet 1 and the driving electromagnet 12 release, advancing the ratchets 22 and 21 respectively, another step. When the electromagnet 12 releases, the operating circuit is again closed and the cycle of operations is repeated, until the brush 57 finally comes to rest upon either the terminal 58 or the terminal 59 indicating the normal position of the switch. With the brush 57 resting upon either the terminal 58 or the terminal 59, the operating circuit as previously traced is permanently opened and the electromagnets 1 and 12 are deenergized, preventing the further operation of the selector switch.

An alternative method for restoring the switch to normal is shown in Fig. 6. In this case, when the sensitive electromagnet 1 is moved off normal, cam 30 which normally is in engagement with the stud 31, is rotated, and the contact springs 32 and 33 are closed. When it is desired to return

the selector switch to the normal position, conductor 60 is connected to ground and contact 61 is connected to battery. An obvious circuit is now completed to operate the sensitive electromagnet 1 by way of the self-interrupter contact 62. The ratchet 22 is accordingly rotated step-by-step until in the normal position of the ratchet, the cam 30 or some similar cam is brought into contact with the stud 31, opening the contact springs 32 and 33, thus preventing the further operation of the sensitive electromagnet 1.

The driving electromagnet 12 which is not shown in Fig. 6, will be returned to normal by way of a circuit arrangement such as the one shown in Fig 4 which was used for advancing it from the normal position when the sensitive electromagnet 1 was set under control of the dial 36.

The continued operation of a selector switch causes minute particles of metal and of dust to settle upon the terminals of the bank of the selector switch. These particles tend to collect at the bottom of the switch bank under the influence of gravity. Heretofore in switches of this general character, it has been customary to rotate the brushes in such a direction that any suction which may be created by them in rotating tends to draw the particles of dust and metal back into the bank. To overcome this difficulty, and at the same time to assist in removing the dust and metal particles from the terminal bank, the brushes of the switch in the present invention are designed to create a suction and are caused to rotate in a direction such that the suction produced by the brushes in rotating tends to aid the force of gravity exerted upon dust and metal particles lodged in the switch bank. To accomplish this, it has been necessary to reverse the switch brushes 54 in a direction opposite to the one heretofore used.

What is claimed is:

1. In a stepping mechanism, a device responsive to impulses, a driven member operated thereby, a stepping magnet, a driven member operated thereby, means for mechanically inter-relating the two driven members aforesaid, means for supplying impulses to the impulse responsive device whereby it is operated and its driven member is set, means responsive to the movement of the driven member last mentioned, whereby the stepping magnet is operated and its

driven member is caused to be stepped until the inter-relation between the driven members is once more resumed.

2. In a stepping mechanism, two electromagnets, driven members individual to each of them having a definite mechanical inter-relationship, means for supplying impulses to one of the electromagnets whereby it sets its driven member and changes the inter-relationship first existing, means responsive to the movement of the driven member aforesaid for operating the other electromagnet which causes its driven member to be stepped until the inter-relation between the driven members is once more resumed.

3. In a stepping mechanism, an impulse responsive device, a driven member operated thereby, a second driven member, a stepping magnet for operating said second driven member, cooperating cams on said driven members, contacts controlled by said cams, and a circuit for said stepping magnet closed by said contacts when said first driven member is moved relative to said second driven member.

4. In a stepping mechanism, an impulse responsive device, a driven member rotatable thereby, a second driven member, a stepping magnet for operating said second driven member, said members being laterally movable with respect to each other, cooperating cams on said members, said cams being effective to cause said lateral movement when one of said members is rotated with respect to the other, contacts controlled by said cams, and a self-interrupting circuit for said stepping magnet closed by said contacts.

5. A unitary electromagnetic mechanism for driving a ratchet comprising an electromagnet, an armature therefor, a pawl secured to the armature, said electromagnetic device, unitarily adjustable with respect to the ratchet.

6. In a selector switch, a stepping magnet for operating said switch, a contact controlling mechanism unitary in form controlled by said magnet, a pivot for attaching said contact mechanism to the stationary portion of said selector switch, and means for rocking said contact mechanism on said pivot whereby the adjustment of the contact controlling device is obtained.

In witness whereof, I hereunto subscribe my name this 29th day of July A. D., 1924.

MERLE PEABODY CHAPLIN.
